(57) **CLAIM**

The ornamental design for a lighting fixture, as shown and described.

DESCRIPTION

FIG. 1 is a front perspective view from below of a lighting fixture according to the new design;

FIG. 2 is a rear perspective view from above thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top view thereof;

FIG. 8 is a bottom view thereof;

FIG. 9 is a front perspective view from below thereof, but shown illuminated;

FIG. 10 is a rear perspective view from above thereof;

FIG. 11 is a front elevational view thereof;

FIG. 12 is a left side elevational view thereof;

FIG. 13 is a right side elevational view thereof;

FIG. 14 is a rear elevational view thereof;

FIG. 15 is a top view thereof; and,

FIG. 16 is a bottom view thereof.

The equal length broken lines in the drawings illustrate portions of the lighting fixture, and the long dash-short dash lines represent the boundaries of the claimed design. None of the broken lines form part of the claimed design.

The stippling shown in FIG. 10 is solely for the purpose of representing the appearance of illumination and does not represent texture or surface ornamentation.
